SHAVER ASSEMBLING TOOL

Edward J. Vrabel, Stratford, Conn., assignor to Sperry
Rand Corporation, New York, N.Y.

Filed Oct. 12, 1972, Ser. No. 299,732

Term of patent 14 years

Int. Cl. D8—05

U.S. Cl. D8—14

FIG. 1 is a top, left end and side perspective view of the shaver assembling tool showing my new design;

FIG. 2 is a top, right end, and side perspective view;

FIG. 3 is a top plan view;

FIG. 4 is an enlarged elevational view;

FIG. 5 is an enlarged bottom plan view;

FIG. 6 is an enlarged right end view; and,

FIG. 7 is an enlarged left end view thereof.

I claim:

The ornamental design for a shaver assembling tool, substantially as shown and described.
